RICHARD A. BIRD, OF DETROIT, MICHIGAN.

BOTTLE STOPPER AND PROCESS FOR PRODUCING THE SAME.

Application filed February 11, 1925. Serial No. 8,390.

This invention relates to a process for producing bottle stoppers and to the stoppers themselves, and its object is to provide a stopper which will be unobjectionable from a medical stand point, which shall have a tab whereby it may be removed from the bottle, and which can be produced at moderate cost.

In the accompanying drawing, Fig. 1 is a top plan view of this improved bottle stopper. Fig. 2 is a section on the line 2—2 of Fig. 1. Fig. 3 is a top plan view of sheet from which the stoppers have been severed but not removed.

Similar reference characters refer to like parts throughout the several views.

The present stoppers, like others now on the market, are cut from a sheet 1 of pulp board, which, while a homogeneous material, usually has a tendency to layer, so that it can be readily split. The sheet may be passed through a sewing machine, once, if the machine is of the multiple needle type, otherwise as often as is necessary to form the lines 2 of stitches of cotton or other fibrous thread. Or these stitches may be formed by hand. The sheet is then properly sheared, preferably by a cutting machine where the disks 3 are severed from the sheet to form stoppers, and at the same time, the sheet is cut part-way through to form the tongues or tabs 4 which are partially surrounded by these cuts 5. But this cutting may be done by hand. These cuts are so positioned that the line of stitches 2 of each disk is at the base or unsevered portion of the tab and that each disk is reinforced at this line to prevent it from splitting which prevents the tab from being torn out when the stopper is being removed from a bottle.

These sheets 1 may be printed before or after the sewing so that any desired insignia or words may appear upon the stoppers, and the sheets may be impregnated with paraffine on one or both sides or with similar water-proofing material before the stoppers are severed, or the stoppers may be impregnated on their lower sides after they are severed, or the paraffining may be omitted entirely, as may be deemed advisable. In order to seal the holes made by the needle while running the stitches, the pulp board

may be compressed at this line or the entire stopper may be compressed, which will usually prevent the passage of air or the liquid contents of the bottle.

I have found that when the stoppers are inserted to close bottles, that sufficient moisture is usually absorbed from the contents to cause the tabs 4 to lift out of the pockets in which they lie, the pulp board splitting to free the tabs. The sewing being done with sanitary cotton thread, no metal can come in contact with the contents of the bottles.

The details of this process and of the stopper may be changed by those skilled in the art without departing from the spirit of my invention as set forth in the following claims.

I claim:

1. The process of forming bottle stoppers which consists in sewing a line of stitches in a sheet of pulp board and then cutting the sheet to form stoppers in such a manner that the stitches run across each stopper, and at the same time so cutting the sheet that a portion of each stopper is partially surrounded by a cut which extends a limited distance through the stopper so as to produce a lifting tab whose unsevered edge is attached to the body of the stopper by means of said stitches.

2. The process of forming bottle stoppers which consists in sewing a line of stitches in a sheet of pulp board, then compressing the pulp-board to close the holes made by the needle, and then cutting the sheet to form stoppers in such a manner that the stitches run across each stopper, and at the same time so cutting the sheet that a portion of each stopper is partially surrounded by a cut which extends a limited distance through the stopper so as to produce a lifting tab whose unsevered edge is attached to the body of the stopper by means of said stitches.

3. A bottle stopper, cut from a blank having a line of stitches therein of sufficient length to produce anchoring means for a plurality of tabs, said stopper having a tab portion cut therefrom and a line of stitching at the base thereof, said line of stitching constituting the chord of a circle.

RICHARD A. BIRD.
